ABSTRACT

A machine for forming stays on four edges of a carton. The machine includes a mandrel which drives a carton blank provided with stays between upright stay forming members and upright side panel forming members to fold side panels against the mandrel and to partially form stay members. Further advance of the mandrel causes the front and rear panels to engage forming members to be folded to a position substantially perpendicular to the central panel with outwardly extending portions of the stay members opposite edge portions of the end panels. Stay forming and crimping members are advanced into engagement with the outwardly extending portions of the stay members to drive prongs thereof into edge portions of the end panels and to crimp the prongs therein.

QUAD STAYING MACHINE

This invention relates to a box-making machine. More particularly, this invention relates to a machine for making boxes having metal stay members at edges thereof.

An object of this invention is to provide a machine which folds a carton blank having stay members mounted thereon and crimps the stay members in position.

Briefly, this invention provides a machine into which carton blanks are fed. Each blank includes four stay members mounted on opposed front and rear panels. A mandrel engages a central panel of the blank and forms the carton blank against first forming members which fold opposed side panels into position and against stay forming members which partially form the stay members. Then the front and rear panels are folded into upright position with the partly formed stay members opposite crimping members. Further advance of the mandrel causes the crimping members to advance toward the mandrel in unison to fold and crimp the four stay members into position reinforcing edges of the carton formed from the blank.

The above and other objects and features of the invention will be apparent to those skilled in the art to which this invention pertains from the following detailed description and the drawings, in which:

FIG. 1 is a view in side elevation of a box making machine constructed in accordance with an embodiment of this invention, supports therefor being partly broken away;

FIG. 2 is a view in rear elevation of the machine shown in FIG. 1 with a stop member thereof being removed to reveal interior structure;

FIG. 3 is a fragmentary perspective view of the machine, a carton blank being shown in association therewith, hinge lines in the carton blank being shown in dashed lines;

FIG. 4 is a fragmentary enlarged view in section taken on the line 4—4 in FIG. 2 showing a carton blank at a carton forming station;

FIG. 5 is a fragmentary view in section taken generally on the same line as FIG. 4 but showing the carton blank partly formed;

FIG. 6 is an enlarged view in section taken on the line 6—6 in FIG. 2;

FIG. 7 is a perspective view showing crimping members and supports therefor;

FIG. 8 is a fragmentary view in upright section showing the crimping members in association with a carton blank and a carton forming mandrel in a first position;

FIG. 9 is a fragmentary view in upright section showing the crimping members in association with the carton blank and the carton forming mandrel in a second position;

FIG. 10 is a fragmentary view in upright section showing the crimping members in association with the carton blank and the carton forming mandrel in a third position;

FIG. 11 is a fragmentary perspective view of a corner of a carton before completion of folding and attaching of a stay member;

FIG. 12 is a perspective view of a carton formed on the machine;

FIG. 13 is a fragmentary view in section taken on the line 13—13 in FIG. 1, an alternate position of drive

members of the machine being shown in dot-dash lines;

FIG. 14 is a fragmentary schematic view showing construction of a carton discharge arrangement of the machine;

FIG. 15 is a fragmentary enlarged sectional view showing details of a crimped portion of one of the stays together with fragmentary portions of the mandrel and one of the crimping members at an edge of the carton; and

FIG. 16 is a fragmentary view in section taken on the line 16—16 in FIG. 5.

In the following detailed description and the drawings, like reference characters indicate like parts.

In FIGS. 1-3 inclusive is shown a carton forming machine 20 which is constructed in accordance with an embodiment of this invention and which includes upright frame bars 21 and 22 (FIGS. 2 and 3) which are linked by cross bars 23 and 24 (FIGS. 1 and 3). The cross bars are shimmed out from the upright bars 21 and 22 by shims 26 and 27 (FIG. 3). Spaced horizontal plates 28 and 29 mounted on the cross bars 23 and 24 define an enclosed space 30 between the cross bars 23 and 24. Upright frame plates 31 and 32 are mounted on the cross bars 23 and 24, respectively, inside the space 30 and extend upwardly therefrom. A third upright frame plate 33 (FIG. 1) is supported in parallelism with the plates 31 and 32 by fasteners 34 mounted in the plates 31 and 32 and fasteners 341 mounted in the cross bar 24. A motor 36 (FIGS. 1 and 2) mounted on a plate 37 supported on upper edges of the upright frame plates 31, 32 and 33 drives a motor shaft 38 on which a pulley 39 is mounted. A belt 40 runs on the pulley 39 and on a driven pulley 42 carried by a shaft 421. The shaft 421 carries a pinion 43 which drives a spur gear 44 mounted on a shaft 46 to drive a pinion 47 mounted on the shaft 46. The pinion 47 in turn drives a spur gear 48 rotatably mounted on a shaft 49. The shafts 421, 46 and 49 are rotatably mounted in bearings, not shown in detail, carried by the plates 32 and 33. During operation of the machine, the shafts 421 and 46 are driven continuously. A single revolution clutch 51 is mounted on the shaft 49. When a pivotally mounted stop actuator bar 52 is swung counterclockwise from its FIG. 2 position, a stop lug 53 (FIG. 1) is released to be received in a slot (not shown) in a hub 531 of the gear 48 so that the clutch 51 connects the shaft 49 to the spur gear 48 for a single turn of the shaft 49 at the end of which the stop lug 53 is again engaged by the stop actuator 52 to cause release of the clutch 51. A friction brake 54 having shoes which engage the shaft 49 under pressure of a compression spring 55 prevents overrunning movement of the shaft 49. The brake 54 is linked to the plate 33 by a pin 56 mounted in the plate 33. The brake continuously restrains the shaft 49 but, when the clutch is engaged to provide a driving force, the braking resistance is overcome by the driving force. The stop actuator bar 52 is urged to the FIG. 2 position by a tension spring 57. The stop actuator bar 52 is pivotally mounted on a shaft 58 mounted on the plate 33. A T-shaped stop lifter 59 is pivotally mounted on a stub shaft 60 mounted on the plate 33 with the head thereof engaging the stop actuator bar 52. A stop release rod 61 extends upwardly from the stop lifter 59 to a solenoid 62 (not shown in detail). When the solenoid 62 is energized, the stop release rod 61 is raised to swing the stop lifter 59 counterclockwise as shown in FIG. 2 to cause counterclockwise swinging of the

stop actuator bar 52 for releasing the clutch 51 to engaged position. As shown in FIG. 13, a crank 63 is mounted on the shaft 49. The crank 63 is linked to a reciprocating upright bar 64 by a link 66. The reciprocating upright bar 64 is guided for up and down movement by roller guides 67 mounted on the plate 31. During one turn of the shaft 49, the crank 63 turns from the full line position of FIG. 13 through the dot-dash line position at which the crank is indicated at 63A and the link at 66A back to the full line position, and the reciprocating upright bar 64 makes one down and up movement. The structure described to this point is similar in structure and operation to conventional punch press structures and the like. A box forming mandrel 69 (FIG. 3) is mounted on the lower end of the reciprocating upright bar 64 and moves down and up therewith.

Carton blanks 71, one of which is shown in FIG. 3, are fed to the machine over an entry table assembly 711. The entry table assembly 711 includes inverted U-shaped frames 72 and 73 (FIG. 1) which are separate from and independent of the frame of the machine proper. Horizontal bars 74 and 76 supported on the frames 72 and 73 support a crosswise frame plate 77 which spans the bars 74 and 76. Angle-shaped guide members 78 and 79 (FIG. 3) are mounted on the crosswise frame plate 77. Fasteners 81 (only one of which is shown) mounted in the plate 77 extend through slots 82 and 83 in the guide members 78 and 79 respectively, to hold the guide members 78 and 79 in adjusted position.

The carton blank 71 (FIG. 3) includes a rectangular central panel 84, rectangular side panels or flaps 86 and 87 hinged to the central panel 84 at hinge lines 88 and 89, respectively, a front panel or flap 91 hinged to the central panel 84 at a hinge line 92 and a rear panel or flap 93 hinged to the central panel 84 at a hinge line 94. The panels 84, 86, 87, 91 and 93 are integrally formed of stiff paperboard. Metal stay members 96 and 97 are attached at opposite side edges of the front panel 91. Metal stay members 98 and 99 are attached at opposite side edges of the rear end panel 93. As shown in FIG. 11, the stay member 99 includes an elongated sheet metal body having a central row of perforations 101 which provide a line of weakening along which the body of the stay member can be folded. In addition, metal of the stay member is pierced and shaped at rows of openings 102 and 103 to form prongs 104 (FIG. 15) which can be imbedded in and crimped over into material of the carton blank 71 to attach the stay member 99 thereto. As shown in FIGS. 3 and 11, one edge portion of each metal stay member, in which the openings 103 are located, extends outwardly from the flap or panel to which the opposite edge portion of the stay member is attached, as indicated at 1031 in FIG. 11.

The carton blank 71 is fed into the machine by a drive roll 106 and an idle roll 107 (FIG. 3). Collars 108 and 109 on the idle roll 107 grip the carton blank 71 against the roll 106 as shown in FIG. 6. The roll 106 is driven by a belt 110 (FIG. 3) which runs on a pulley 111 carried by a motor shaft 112 driven by a motor 113. The rolls 106 and 107 are rotatably mounted in bearing bores (not shown) in bearing blocks 1131 and 1132. The bearing blocks 1131 and 1132 are adjustably mounted on upright portions 1133 and 1134, respectively, of the frame 72. The motor 113 is mounted on an appropriate bracket (not shown) carried by the up-

right portion 1133. As shown in FIG. 6, the carton blank 71 is advanced beneath the mandrel 69 until a leading edge of the front panel 91 of the carton blank is received in an angle-shaped switch operator and stop 114. As shown in FIG. 1, the stop 114 is mounted on a crank bar 116 which is pivotally mounted on an auxiliary frame 117. When the stop 114 is engaged by one of the carton blanks, the stop swings to the right as shown in FIG. 1 sufficiently to actuate a limit switch 118. Actuation of the limit switch 118 energizes the solenoid 62 to cause engagement of the single revolution clutch 51 starting a cycle of the mandrel 69. The carton blank 71 is released by the drive roll 106 and the collars 108 and 109 as the stop actuates the switch 118 and the mandrel 69 starts downwardly.

The front panel 91 of the carton blank 71 is guided into position by guide members 119 and 121 (FIG. 2). The guide members 119 and 121 are similar in construction and only the guide member 121 will be described in detail. As shown in FIG. 6, the guide member 121 includes a body 122 provided with a dovetail slot 123 in which a transverse bar 124 is received. A screw fastener 126 threaded in the body 122 and engaging the transverse bar 124 holds the guide member 121 in position thereon. A guide lug 127 extends upwardly from the body 122. The guide lug 127 includes an angled face 128 (FIGS. 4 and 5) and a carton blank positioning face 129, which extends parallel to the direction of movement of the carton blanks. A shoulder 131 (FIG. 30) 6) at the upper end of the body 122 underlies an outwardly projecting portion 1311 of the stay member 97 as shown in FIG. 4 when the carton blank is at a carton forming station. The guide members 119 and 121 (FIGS. 2 and 3) position the carton blank with the stop 114 (FIG. 5) limiting advance of the carton blank so that, when the carton blank stops at the carton forming station, the central panel 84 is centered under the mandrel 69. Rear guide members 132 and 133 (FIG. 3) are mounted on a second transverse bar 134 in the manner 35 that the rear guide member 133 is shown in FIGS. 5 and 6. A dovetail slot 136 (FIG. 6) in the rear guide member 133 receives the transverse bar 134. A thumb screw 1137 threaded in the rear guide member 133 engaging the transverse bar 134 holds the rear guide member 133 in position on the transverse bar 134. When the carton blank 71 stops, outwardly extending edges of the stay members 98 and 99 (FIG. 3) overlie the rear guide members 132 and 133 as shown in FIG. 4.

The transverse bar 124 is mounted on studs 137 (FIGS. 2 and 5) and 138 (FIG. 2) mounted in a block 139, and studs 141 and 142 mounted in a block 143. The blocks 139 and 143 are mounted on the upright frame bars 21 and 22, respectively. The studs 137 and 138 are mounted in bores 144 and 146 (FIG. 16), respectively, in the block 139. The studs 141 and 142 are mounted in similar bores (not shown) in the block 143. Thumb screws 147 and 148 threaded in the transverse bar 124 bear on the blocks 139 and 143, respectively, in the manner that the thumb screw 147 is shown in FIG. 16 to hold the transverse bar 124 in spaced relationship to the blocks 139 and 143. Nuts 1371, 1381, 1411 and 1421 (FIG. 2) threaded on the studs 137, 138, 141 and 142, respectively, limit outward movement of the transverse bar 124. The transverse bar 134 is similarly mounted on studs 149 and 151 (FIG. 3) mounted in the block 139 and on similar studs (not shown) mounted in the block 143. Thumb screws 152,

only one of which is shown, threaded in the transverse bar 134 engage the blocks 139 and 143 to hold the transverse bar 134 in position.

Elongated rods 153 and 154 (FIG. 3) are positioned between the transvers bars 124 and 134. Details of construction of the rods 153 and 154 and components supported thereby are similar, and only the rod 153 and associated components will be described in detail. The rod 153 extends through a bore 156 in the block 132 and a similar bore 157 in the upright frame 21. Nuts 158 and 159 (FIG. 4) threaded on the rod 153 hold the rod 153 in adjusted position. A block 161 is mounted on the elongated rod 153. An extension portion 162 of the block 161 carries a channel-shaped flap forming member 163. Crosswise rods 164 and 166 are mounted in the block 161. The rods 164 and 166 are above and below and engage upper and lower faces 167 and 168 (FIG. 2), respectively, of a necked-in portion 169 of the transverse bar 124 as shown in FIG. 7. The crosswise rods 164 and 166 also engage upper and lower faces 171 and 172, respectively, of a necked-in portion of the transverse bar 134. Cranks 174 and 176 are pivotally mounted on the crosswise rods 164 and 166, respectively. An L-shaped crimping and forming member 177 is mounted on free ends of the cranks 174 and 176 forming a parallelogram linkage therewith. As shown in FIGS. 8, 9 and 10, the cranks 174 and 176 and the member 177 can swing downwardly. A tension spring 178, which extends between lugs 179 and 181 mounted on the cranks 174 and 176, respectively, urges the cranks 174 and 176 and the member 177 to the position shown in FIGS. 7 and 8 at which stop lugs 182 and 183 on the cranks 174 and 176 engage the member 177 limiting upward movement. A roller 184 is rotatably mounted on a flange 186 of the member 177 to rotate on an axis parallel to the rods 164 and 166 and extending crosswise of the direction of mandrel advance. An upright face 1861 on the body of the member 177 is opposed to the mandrel 69. The face 1861 extends parallel to the direction of movement of the mandrel and to the opposed face of the mandrel. In a similar fashion, a second L-shaped crimping and forming member 187 is supported on cranks 188 and 189 (FIG. 5) which are also pivotally mounted on the rods 164 and 166. Also, in a similar fashion, a block 191 mounted on the elongated rod 154 supports rods 192 and 193 (FIG. 4) on which cranks 194, 196, 197 and 198 are pivotally mounted. L-shaped crimping and forming members 199 and 201 are supported on the last mentioned cranks.

As the mandrel 69 moves downwardly engaging the central panel 84 of the carton blank 71, the side panel 87 engages the flap forming member 163 so that the side panel 87 is folded upwardly to the position shown in FIG. 5. Similarly, the side panel 86 (FIG. 4) engages a flap forming member 1631 supported by the block 191 to be folded upwardly. At the same time the front panel 91 is forced downwardly causing the stay members 96 and 97 to be partially folded into the position that the member 97 is shown in FIG. 5. The rear panel 93 is forced downwardly between the guide members 132 and 133 to cause partial folding of the stay members 99 and 98 to the position at which the stay member 99 is shown in FIG. 5. As the carton blank is moved downwardly during the first portion of its downward movement after engaging the carton blank, the outer edges of the stay members 96 and 97 (FIG. 4) engage

upright faces 203 and 204 of the guides 119 and 121, respectively. At this time the outer edges of the rear stay members 98 and 99 engage upright faces 206 and 207 of the rear guide members 132 and 133, respectively.

As the mandrel 69 progresses further downwardly, the front panel 91 (FIG. 6) engages the transverse bar 124 and the rear panel 93 engages the transverse bar 134. Upper inner edges 209 and 211 of the transverse bars 124 and 134 are beveled at 45° angles to the path of mandrel advance to guide the front and rear panels to swing upwardly to the position shown in FIG. 5 at which the outwardly extending partially folded edges of the stay members are opposed to the folding and crimping members in the manner that the stay members 97 and 99 are shown in FIG. 5 opposite the folding and crimping members 177 and 187, respectively. As the mandrel 69 moves further downwardly, the central panel 84 of the carton blank is brought into engagement with the roller 184 of the folding and crimping member 177, as shown in FIG. 8 and with similar rollers of the other folding and crimping members. As the mandrel 69 moves downwardly further to the FIG. 9 position, the folding and crimping members swing downwardly with the cranks on which they are mounted and inwardly toward the mandrel 69 to complete folding of the stay members and to cause crimping of the prongs 104 of the stay members to the crimped position shown in FIG. 15. As the mandrel 69 advances further downwardly to the FIG. 10 position, the folding and crimping members swing outward to permit the lower edge of the mandrel 69 to move past the roller 184 and the other similar rollers. When the mandrel 69 approaches the bottom of its cycle, a valve operator 213 (FIG. 13) mounted on the upright bar 64 engages a valve button 214 of a valve 216 which is supported on an extension 217 (FIG. 3) of the upright plate 31 to operate the valve 216. The valve 216 is connected to a source of air under pressure by a supply line 219 (FIG. 14). When the valve 216 is opened by actuation of the valve operator 213, air under pressure from the source is supplied through the valve 216 and a line 221 to a channel 222 inside the upright bar 64. An air cylinder 223 is formed inside the upright bar 64, and the channel 222 supplies the air under pressure to the upper end of the cylinder 223. A piston 224 moves in the cylinder 223. A shaft 226 attached to the piston 224 carries a plunger or head 227 which engages the central panel 84 of a completed carton 231, and when air under pressure is supplied to the cylinder 223, the head 227 is projected downwardly as indicated at 227A to cause the completed carton 231 to be discharged from the mandrel. As the mandrel 69 starts to return upwardly, the valve button 214 is released so that the valve 216 moves to its other or released position at which the line 221 is connected to an exhaust line 236 (FIG. 14), and the air in the cylinder 223 can be discharged therethrough. A compression spring 237 causes retraction of the piston 224, the shaft 226 and the head 227. The completed carton 231 can fall onto an appropriate conveyor 239 (FIG. 1).

The carton forming machine illustrated in the drawings and described above is subject to structural modification without departing from the spirit and scope of the appended claims.

Having described my invention, what I claim as new and desire to secure by letters patent is:

1. A carton forming machine for shaping a carton blank having a central panel, opposed front and rear panels having stay members mounted thereon, and opposed side panels, which comprises upright stay forming members and upright side panel forming members at a carton forming station, means for positioning the carton blank at the carton forming station with the stay forming members underlying outwardly extending portions of the stay members and with the side panel forming members underlying the side panels, the carton positioning means including a stop engageable with an edge portion of the front panel of the carton blank when the carton blank is disposed at the carton forming station, a switch operator connected to the stop, actuation of the switch operator causing operation of the mandrel advancing means when the carton blank is at the carton forming station, a mandrel, means for advancing the mandrel into engagement with the central panel to advance the side panels into engagement with the side panel forming members to be formed to positions extending transversely of the central panel and to advance the front and rear panels between pairs of the stay forming members to cause inward folding of the stay members between the stay forming members, front and rear panel forming members, further advance of the mandrel causing the front and rear panels to be folded against the front and rear panel forming members to positions extending transversely of the central panel to dispose the outwardly extending portions of the stay members opposite edge portions of the side panels, stay forming and crimping members, and means for advancing the stay forming and crimping members into engagement with the outwardly extending portions of the stay members to drive prongs thereof into the edge portions of the side panels and to crimp the prongs therein.

2. A carton forming machine for shaping a carton blank having a central panel, opposed front and rear panels having stay members mounted thereon, and opposed side panels, which comprises upright stay forming members and upright side panel forming members at a carton forming station, means for positioning the carton blank at the carton forming station with the stay forming members underlying outwardly extending portions of the stay members and with the side panel forming members underlying the side panels, the carton positioning means including a stop engageable with an edge portion of the front panel of the carton blank when the carton blank is disposed at the carton forming station, a driven roller means and a second roller means arranged to grip the carton blank against the driven roller means for advancing the carton blank to the carton forming station, the roller means releasing the carton blank when the carton blank engages the stop, a mandrel, means for advancing the mandrel into engagement with the central panel to advance the side panels into engagement with the side panel forming members to be formed to positions extending transversely of the central panel and to advance the front and rear panels between pairs of the stay forming members to cause inward folding of the stay members between the stay forming members, front and rear panel forming members, further advance of the mandrel causing the front and rear panels to be folded against the front and rear panel forming members to positions extending transversely of the central panel to dispose the outwardly extending portions of the stay members opposite edge

portions of the side panels, stay forming and crimping members, and means for advancing the stay forming and crimping members into engagement with the outwardly extending portions of the stay members to drive prongs thereof into the edge portions of the side panels and to crimp the prongs therein.

3. A carton forming machine for shaping a carton blank having a central panel, opposed front and rear panels having stay members mounted thereon, and opposed side panels, which comprises upright stay forming members and upright side panel forming members at a carton forming station, means for positioning the carton blank at the carton forming station with the stay forming members underlying outwardly extending portions of the stay members and with the side panel forming members underlying the side panels, a mandrel, means for advancing the mandrel into engagement with the central panel to advance the side panels into engagement with the side panel forming members to be formed to positions extending transversely of the central panel and to advance the front and rear panels between pairs of the stay forming members to cause inward folding of the stay members between the stay forming members, front and rear panel forming members, further advance of the mandrel causing the front and rear panels to be folded against the front and rear panel forming members to positions extending transversely of the central panel to dispose the outwardly extending portions of the stay members opposite edge portions of the side panels, stay forming and crimping members, the means for positioning the carton blank at the carton forming station including guide lugs on the stay forming members outboard of portions thereof which underly the stay members mounted on the front panel, the guide lugs being engageable with the outer edges of the last mentioned stay members for guiding the front panel, and means for advancing the stay forming and crimping members into engagement with the outwardly extending portions of the stay members to drive prongs thereof into the edge portions of the side panels and to crimp the prongs therein.

4. A carton forming machine for shaping a carton blank having a central panel, opposed front and rear panels having stay members mounted thereon, and opposed side panels, which comprises upright stay forming members and upright side panel forming members at a carton forming station, means for positioning the carton blank at the carton forming station with the stay forming members underlying outwardly extending portions of the stay members and with the side panel forming members underlying the side panels, a mandrel, means for advancing the mandrel into engagement with the central panel to advance the side panels into engagement with the side panel forming members to be formed to positions extending transversely of the central panel and to advance the front and rear panels between pairs of the stay forming members to cause inward folding of the stay members between the stay forming members, front and rear panel forming members, further advance of the mandrel causing the front and rear panels to be folded against the front and rear panel forming members to positions extending transversely of the central panel to dispose the outwardly extending portions of the stay members opposite edge portions of the side panels, stay forming and crimping members, each of the stay forming and crimping members including a body having an upright face extending

substantially parallel to the opposed face of the mandrel, a pair of cranks pivotally connected to the body, and means for supporting pivots of the cranks so that the cranks and the body form a parallelogram linkage, and means for advancing the stay forming and crimping members into engagement with the outwardly extending portions of the stay members to drive prongs thereof into the edge portions of the side panels and to crimp the prongs therein.

5. A carton forming machine as in claim 4 wherein the body of each of the stay forming and crimping members includes a flange opposed to the mandrel, and means on the flange engageable by the central panel of the carton blank opposite the mandrel as the mandrel advances so that the stay forming and crimping member is advanced by advance of the mandrel.

6. A carton forming machine as in claim 5 wherein the means engageable by the central panel of the carton blank is a roller pivotally mounted on the flange for rotation about an axis parallel to the pivots of the cranks.

7. A carton forming machine as in claim 4 wherein

the stay forming and crimping members swing from a first retracted position at which the upright face of each stay forming and crimping member is spaced from the mandrel a sufficient distance to accommodate the opposed stay member and end panel, through an intermediate position at which the upright faces grip the stay members and end panels against the mandrel to a second retracted position at which the mandrel can pass between flanges of the stay forming and crimping members, and means is provided for urging the stay forming and crimping members to the first retracted position.

8. A carton forming machine as in claim 7 wherein means is provided for discharging a formed carton from the mandrel when the stay forming and crimping members are in the second retracted position.

9. A carton forming machine as in claim 8 wherein the means for discharging the formed carton includes a plunger mounted on the mandrel, engageable with the central panel, and extendable outwardly of the mandrel, and means for extending the plunger when the mandrel passes between the flanges.
